PRESSURE RELIEF ATTACHMENT

William P. Huffman and Frederick F. Rike,
Dayton, Ohio, assignors to Buckeye Iron and
Brass Works, Dayton, Ohio, a corporation of
Ohio

Application January 29, 1932, Serial No. 589,686

16 Claims. (Cl. 137—71)

This invention relates to an attachment adapted to be used in connection with the delivery pipe of a gasoline dispensing apparatus and to act as an expansion chamber for relieving the pressure 5 in the delivery pipe and its connections due to the expansion of the gasoline therein, and the formation of gases or vapors arising from vaporization of the liquid, caused by the heat of the sun acting in warm weather on the pipe and its connections; or where such expansion is due to any 10 condition which causes an increase in such pressure. It is particularly the object of this invention to provide a reservoir of an expansible character so as to yield more and more as the excess 15 pressure may increase, and to locate such attachment between or adjacent to the delivery pipe and the meter.

It is a further object of this invention to provide a reservoir in which the interior chamber is 20 made expansible by a diaphragm or partition capable of moving or yielding within the reservoir casing, and held by spring means so as to yield as the pressure increases; or the expanded liquid and/or gases or vapors increase in volume.

25 Referring to the drawing:

Figure 1 is a vertical section through the upper part of the casing showing one part of the delivery pipe and hose, with applicants' attachment properly connected to the delivery pipe.

30 Figure 2 is a vertical section through the attachment.

Figure 3 is a section on the line 3—3 of Figure 2.

Figure 4 is a section on the line 4—4 of Figure 2.

Under normal operation of any gasoline dispensing apparatus the pressure in the delivery line and the hose, when the valve is open, is ten pounds or less. When the valve is closed this 40 pressure may be increased to twenty pounds, due to the recirculation of the gasoline through the by-pass in connection with the pump. During increased temperature the normal pressure of the gas in the pipe and hose may be increased to 45 such an extent that an explosion would take place and result in bursting either the hose or pipe, or damaging the valve.

Even though these parts are not broken or ruptured, a leaking of gasoline vapors may occur, 50 thereby causing a loss in addition to creating unpleasant odors about the delivery apparatus, and also increasing the danger of fire and explosion. This increase of pressure, due to summer heat, may become as much as forty pounds per square 55 inch or more, and unless the parts are very secure

explosion may result. It is for the purpose of relieving this pressure that the present attachment is provided, and is attached to the delivery pipe between the meter and the hose.

In Figure 1 a part of the upper end of the casing 1 is shown, on one side of which is a dial 2 to indicate the amount of gasoline delivered or dispensed. The gasoline is being dispensed through a supply pipe 3, which delivers the fluid or gasoline to a meter chamber 4, from which a discharge pipe 5 conducts the gasoline to a hose 6. On the free end of this hose is a nozzle and valve 7. The nozzle is for delivering the gasoline into a tank or spout, while the valve controls the opening through the nozzle. As the gasoline passes from the discharge pipe into the hose it passes through a sight gauge 8, usually found in connection with gasoline dispensing apparatus.

The present attachment consists of a casing or cylinder constituting an expansion chamber 75 composed of two parts, a lower shell part 9 and an upper dome-shaped part 10, threaded into the upper cylindrical part of the shell 9. Between the dome and the shell part is a gasket 11. This gasket cooperates with the threaded connection, between the shell and the dome, to form a gas and liquid-tight seal. The part of the shell below the dome is formed into a chamber 12, forming part of an expansion chamber, which is more or less vertical in its disposition and has 85 in its lower end a small inlet opening 13 by which the gas or vapor passes into the chamber 12.

Around the chamber 12 and within the shell is an annular trough 14, which has around it, and forming one of the walls thereof, an annular 90 seat 15. Fitting within the casing or cylinder formed by the dome is a plunger, piston or partition 16. The purpose of this partition or piston is to provide means for increasing the expansion chamber by enlarging the space in the lower part 95 of the housing formed by the shell, partition and part of the dome so that space may be provided for expansion in the liquid or reception of vapors formed from the liquid.

Around the periphery of this plunger is an annular shoulder 17, which has resting thereon one edge of an annular packing 18. This packing may be of leather, rubber or any suitable material, and is cup-shaped, as shown in Figure 2, with the open part extending downwardly from the annular shoulder 17. This packing is held on the shoulder by means of a ring 19 threaded on the piston or plunger above the packing.

There is also provided below the shoulder 17 an annular seat for a garter spring 20. This is a 110

compression spring and tends to hold the packing 18 against the inside walls of the dome 10 as the plunger moves back and forth in the dome.

In the central part of the lower surface of the plunger is provided a seat for a packing 21. This packing is held in place by means of a disc 22, which has on one side thereof a stem 23 threaded into the central part of the plunger, while on the other side there is a guide stem 24 suitably fitting in a hole in a spider 25. The spider serves to guide the stem and the disc 22 as they move vertically.

The disc 22 and the packing 21 are round. The disc is adapted to fit within the annular seat, 15 while the packing is adapted to rest upon the annular seat 15 and form a tight sealing engagement therewith. When the packing 21 is upon the seat 15 the trough 14 is distinctly separated from the chamber 12 so it is possible for an 20 unbalanced condition of pressure to exist between the chamber and the trough, if some means is not provided for relieving this unbalanced condition. This means will be later on described.

Extending downwardly from the top and within 25 in the dome is a boss 26, which has a hole 27 therein. On the upper side of the plunger is a boss 28 into which one end of a guide stem 29 is threaded. The other end of this guide stem fits into the hole 27 and is guided therein by 30 means of the boss 26. This boss 26 and the guide stem 29 tend to aid in the proper positioning of the plunger, and maintaining this plunger in its proper position with relation to the sides of the dome.

35 Between the upper end of the dome and the plunger is a spring 29a, which serves to maintain the plunger in its lower position, with the packing 18 seated upon the annular seat 15. This spring, in addition to maintaining the plunger 40 or piston in its lower seated position, also will serve to limit the upward movement of the plunger because when the coils of the spring contact the plunger cannot be moved farther upwardly.

45 Other means is also provided for limiting the upward movement of the plunger. This means consists of a stop flange 30, extending around the inside of the dome, as shown in Figure 2. This flange may be differently positioned so as to vary the upward limit of the plunger. The size of 50 the spring may also be varied. The spring may be made weaker and also the coils may normally be spaced farther apart than shown in Figure 2, thereby making it possible to increase the range of movement of the plunger or piston; also thereby increasing the amount of space to take care of any expansion that may take place in the liquid, or the amount of vapor that may be received from the liquid.

60 In the shell adjacent one side of the chamber 12 is a pocket 31, circular in shape and vertically located. Extending from the trough 14 downwardly is a passageway 32, which has its lower end connected by means of an inlet 33 to the pocket 31, thereby providing a direct communication 65 between the trough and the chamber 12. This communication is controlled by means of a valve located within the pocket 31.

67 Located at the lower end of this pocket 31 is a packing or washer 34, which has an opening in 70 the center thereof in line with the inlet 33. This packing is held in position by means of an inverted thimble member 35, which has in its upper end one or more outlets 36. This thimble is circular on its interior, and has located therein a 75 hexagonal plug member 37, which serves as a

valve to close the inlet 33. This valve is made of metal and is sufficiently heavy to maintain itself seated on the washer 34 until some considerable pressure accumulates in the passageway 32. After the accumulated pressure has been released by raising the valve the pressure condition between the trough and the chamber is substantially identical. In order to relieve pressure in the upper end of the dome, or to release the accumulation of vapor therein, a discharge cock 38 is provided.

Whenever the gasoline in the various pipes and the hose becomes heated it expands and vaporizes. This expansion is taken care of by means of the attachment herein described. When an increase of pressure is brought about either the liquid or vapor will pass through the inlet 13 in the chamber 12. When the pressure becomes sufficient the plunger is moved upwardly against the action of the spring 29a, thereby providing a space to take care of the increased volume of liquid or the production of vapor. The greater the pressure the higher the plunger will be forced against the action of the spring.

While a plunger or piston has been shown, other 100 movable diaphragm or partition member may be used, the object being to provide a space that will, under pressure, be increased for taking care of the formation of the vapor or the expansion of the liquid. In the present form one means is 105 illustrated for providing an expansion chamber for taking care of the creating of vapors from the expansion of the liquids.

Thus, in effect, there is provided an expansion 110 chamber with means for permitting the flow therein of varying volumes of gases or vapors caused by the evaporation of the contained fluid; and for the accommodation of any expansion in such liquid due to increases in temperature. The prime feature lies in this expansible chamber for 115 this purpose.

Thus also it will be understood that our invention 120 comprises a piston or partition of differential diameters, larger and smaller, with a seat for the smaller area, with a spring to yieldingly permit the partition or piston to be held to such seat and to yield with varying pressures of the gases or vapors and the expanding liquid, with means for admitting the flow therein first to the smaller area of the first partition or piston.

When the pressure is sufficient the smaller area 125 is lifted from its seat and the expansion pressures then reach the larger area, after which both the larger and smaller areas are acted upon by such pressure, while with a sufficient lowering of the 130 pressure, as by reduction of the temperature or the opening of the nozzle valve, the spring will react and reseat the smaller area of the partition or piston. These operations repeat themselves from time to time, but always with the effect 135 of yielding to the pressures and thereby enlarging the interior of the expansion chamber.

When the valve in the hose nozzle is closed, if the motor is allowed to operate the pump for more or less a period, as by oversight of the attendant, 140 then the gasoline in the delivery pipe will by-pass, but the liquid will not be diverted into entering the expansion chamber because during such period the pressure is not sufficient to cause the piston or partition to lift in the chamber, for the 145 reason that at such time only the smaller area of the piston or partition is exposed to the pressure. The pressure is not then great enough, when confined as it then is, to acting on the smaller area, to lift and unseat the piston or partition. Ac- 150

cordingly, none of the gasoline will be diverted into the chamber during the period the motor is running and by-passing the gasoline, and the valve of the nozzle is closed. This acts in turn to preserve the full quantity of gasoline in the delivery pipe and hose by preventing it, or any part of it, from entering the expansion chamber. This period of prevention continues until the pressure is built up a sufficient degree to lift the piston or partition while acting only on the smaller area. After the pressure has sufficiently accumulated to unseat the piston or partition, though acting only on the smaller area, then the pressure will have access to the larger area also. But that will not take place during any period of the by-passing of the liquid.

We desire to comprehend within our invention such modifications as may be embraced within our claims and the scope of our invention.

Having thus fully described our invention, what we claim as new and desire to secure by Letters Patent, is:

1. In a pressure relief attachment, an expansion cylinder having an inlet, a trough around the inlet and a wall between the trough and the inlet, said wall forming a seat, a plunger forming a piston in the cylinder adjacent the inlet, and means tending to hold the plunger on the seat but adapted to yield to pressure, said trough being connected to the inlet by a passageway.

2. In a pressure relief attachment, an expansion casing having an inlet and an annular valve seat around the inlet, a partition in said casing adapted to rest on the seat and be removed therefrom by pressure through the inlet, and means to equalize the pressure on one side of the partition and on opposite sides of the seat when it is on the seat.

3. In a pressure relief attachment, a casing having therein a yielding piston member dividing the casing into two parts and an inlet to admit a fluid to said casing on one side of said member, a seat in the casing around the inlet, and forming a wall of a trough around the inlet, said trough being connected to the inlet by a valve-controlled passageway, sealing means on said member adapted to engage the seat, and means tending to hold the sealing means on the seat so that when the fluid first enters the casing it will press against the sealing means and after the sealing means has been removed from the seat it will press against substantially all of one side of said member.

4. In a pressure relief attachment, a casing consisting of a shell and dome threaded into the shell, said shell having an inlet opening, a trough around the opening, a passageway between the trough and the inlet opening and an annular seat between the opening and the trough, a movable plunger in said dome adapted to rest on the seat, and means tending to hold the plunger on the seat, said plunger when on the seat forming a pressure chamber to give the plunger its initial movement in the formation of a large expansion chamber.

5. In a pressure relief attachment, a casing consisting of a shell and a dome removably attached to the shell, said shell having therein a chamber having an inlet at one end and an annular seat around the other end, and a passageway from adjacent the seat to the chamber, a plunger forming a piston in said dome adapted to rest upon the seat, means in the chamber to guide the plunger, and means tending to hold the plunger on the seat.

6. In a pressure relief attachment, a casing consisting of a shell and a dome attached to the shell, said shell having therein a chamber having an inlet at one end and at the other end an annular seat around the chamber and a trough around the seat, a reciprocating member in said dome adapted to rest upon the seat, means tending to hold said member upon the seat, and means to equalize in one direction the pressure in the chamber and that in the trough when the reciprocating member is on the seat.

7. In a pressure relief attachment, a casing consisting of a shell and a dome, said shell having an extension with a chamber therein having an inlet, an annular seat around one end of the chamber and forming with the adjacent shell structure a trough, means in the casing adapted to rest upon the seat and cooperating with the casing to form with the shell chamber an expansion chamber, a pressure relief between the trough and the chamber, and a guide in the shell chamber to guide the first-named means.

8. In a pressure relief attachment, a casing consisting of a shell and a dome, said shell having an extension forming a chamber having an inlet, an annular seat around one end of the chamber and forming with the adjacent shell structure a trough, means in the casing adapted to rest upon the seat and cooperating with the casing to form with the shell chamber an expansion chamber, a pressure relief between the trough and the chamber, and a guide in the shell chamber to guide the first-named means, said guide consisting of a stem and a spider in the shell.

9. In a pressure relief attachment, a casing consisting of a shell and a dome, said shell having an extension forming a chamber having an inlet, an annular seat around one end of the chamber and forming with the adjacent shell structure a trough, means in the casing adapted to rest upon the seat and cooperating with the casing to form with the shell chamber an expansion chamber, a pressure relief between the trough and the chamber, and a guide in the shell chamber to guide the first-named means, said guide consisting of a stem threaded into said means and a spider in the shell.

10. In a pressure relief attachment, a casing consisting of a shell and a dome, said shell having an extension forming a chamber having an inlet, an annular seat around one end of the chamber, a plunger forming a piston in said dome adapted to rest upon the seat and cooperating with the casing to form with the shell chamber an expansion chamber, a gasket on the plunger to engage the seat, a guide stem threaded into the plunger through the gasket, and means to guide the stem.

11. In a pressure relief attachment, a casing consisting of a shell and a dome, said shell having an extension forming an attaching means forming a chamber having an inlet, an annular seat around the chamber and forming with the adjacent parts of the shell a trough, a plunger forming a piston in the dome adapted to rest upon the seat and be moved off the seat due to pressure in the chamber to form an expansion chamber, and a valve-controlled by-pass from the trough to the chamber.

12. In a pressure relief attachment, a casing having at one end a chamber, an inlet to the chamber and a seat around the chamber forming a trough, a reciprocating member in the

- casing cooperating with the casing to form in combination with the chamber an expansion chamber, and means to by-pass pressure from the trough to the first-named chamber.
- 5 13. In a pressure relief attachment, a casing having at one end a chamber, an inlet to the chamber and a seat around the chamber forming a trough, a reciprocating member in the casing cooperating with the casing to form in combination with the chamber an expansion chamber, and means to by-pass pressure from the trough to the first-named chamber, said means consisting of a passageway having a valve therein.
- 10 14. In a pressure relief attachment, a casing having at one end a chamber, an inlet to the chamber and a seat around the chamber forming a trough, a reciprocating member in the casing cooperating with the casing to form in combination with the chamber an expansion chamber, and means to by-pass pressure from the trough to the first-named chamber, said means consisting of a passageway having a valve therein.
- 15 15. In a pressure relief attachment, a casing having an inlet in one end and a relief cock adjacent the other end, a plunger forming a piston in said casing, means in the casing tending to hold the plunger adjacent the inlet but adapted to yield to pressure on the plunger so that an expansible chamber is formed, a valve in said passageway, and a stop in the casing for the plunger.
- 20 16. In a pressure relief attachment, a casing having an inlet at one end and an outlet at the other end, a plunger forming a piston in said casing, means in the casing tending to hold the plunger adjacent the inlet but adapted to yield to pressure on the plunger to form an expansible chamber, and a flange in the chamber to form a stop for the plunger.
